UNITED STATES PATENT OFFICE

HENRY GINNELL, OF SCARSDALE, NEW YORK, ASSIGNOR TO HILER ENGINEERING & CONSTRUCTION COMPANY, INC., A CORPORATION OF NEW YORK

INCINERATOR GRATE

Application filed June 15, 1929. Serial No. 371,081.

In the construction of large incinerator grates for municipalities and the like, it is customary to form an extended bed for combustion. This bed is principally made up of fixed grate bars and only a small part is adapted to be tilted for dumping. It is necessary, however, for this part to provide a large opening so that tin cans and the like can be dropped through. As the grate bars must be made of heavy material, the operation of the portion of the grate which is dropped is ordinarily rather onerous. According to the present invention, I have designed an arrangement of grates whereby a portion may be dropped down on a pivot but is normally braced so that it is held rigidly in place and is counterweighted from below so that it may easily be moved back into position.

This invention may be readily understood from the illustrative example shown in the accompanying drawings in which Fig. 1 is a plan view, with a portion broken away, of the front part of the grate chamber showing the tilting plates; Fig. 2 is a sectional view of the parts shown in Fig. 1, and also indicating the position of the fixed grates; Fig. 3 is a view of certain of the parts shown in Fig. 2 but in different position, and Fig. 4 is a diagrammatic view showing a slight modification.

The grate chamber is provided with fixed grates 10 in front of which are the movable grates 12, two of which are here shown coupled together to be operated simultaneously. In front of the movable grates 12 is a platform 14. It is noted that the fixed grates 10 are at a slight angle so that after the movable grates 12 have been dropped, rubbish and ashes may easily be raked forward to pass through the opening thus provided.

The tilting grates 12 are pivoted in any desired way as by the integral pins 16 which enter appropriate holes in cross-members 18 running between the platform 14 and the fixed grates 10. At the center lower portion of each grate 12 is a lug 20 to which is pivoted a support arm 22. The support arm 22 is pivoted to the support 24 which

in turn is carried by the squared rock-shaft 26 pivoted to the main frame 28 so that members 22 and 24 form a toggle joint. The arm 22 is provided with a lug 30 and the arm 24 is provided with a lug 32 through which passes a bolt 34 so that the maximum downward movement of the toggle past the dead-center can be readily adjusted. In the present instance, both grates 12 are intended to be operated simultaneously and therefore they are connected to a common rock-shaft 26. Fixed on the shaft 26 is an arm 36 extending through the front frame 28 and provided with a socket 38 intended to receive the operating lever 40. Adjacent the pivot between the members 22 and 24 is hung a weight 42 which is here shown in the form of the ordinary scale weight so that the same may be readily increased or decreased. As shown in Fig. 1 this weight is slightly offset so as not to interfere with the movement of members 22 and 24. While it is preferable to have this weight adjustable, this is not essential and this weight may be cast as an integral part of members 22 and 24, or either of them.

In Fig. 2, members 22 and 24 are shown with their pivots all in line so these members are exactly on dead center. With the parts in this position, the grate 12 will be held in position unless the toggle slips up, and this is prevented by the weight 42. Of course, if desired, bolt 34 could be screwed backward a little bit so that the toggle would be in a more perfect state of equilibrium, but the adjustment should be such that no substantial lifting of grate 12 is necessary to break the toggle upward. When a pull down and out is exerted on lever 40, weight 42 is raised a very short distance, breaking the toggle upward. The weight of grate 12 and of the material resting on it then pushes back on member 22, pushing member 24 up to the position shown in Fig. 3 and lifting weight 42. Weight 42 can be adjusted so that there is a very close approximation to equilibrium between the weight of grate 12 and the downward pull of weight 42. A relatively light upward push on lever 40 will restore the parts

to the aligned position shown in Fig. 2, where they will automatically lock in place.

In some instances the grates are raised a substantial distance above the floor so that it is not practicable to attach the lever directly to the rock shaft 26. In such a case I may provide an auxiliary lever 44 as indicated in Fig. 4. This is provided with a handle 46 and an upwardly extending bar 48 pivoted on the lever 44 and pivoted to member 24' adjacent to toggle joint. The operation of this device will be identical with that heretofore described except that in this instance the weight W may be slightly less than the weight 42 owing to the tendency of members 44 and 48 to counterbalance the weight of the grate 12'.

What I claim is:

1. In combination, a pivoted grate adapted to swing downwardly, a member pivoted to the underside of such grate, a second member pivoted to a fixed support and to said first member to form a toggle joint, means for preventing said toggle from breaking downwardly, means whereby said toggle may be broken upwardly, and a counterweight connected with said members near said toggle joint adapted to assist in preventing said toggle from accidentally breaking upwardly and adapted partly to counterbalance the weight of said grate.

2. In combination, a pivoted grate adapted to swing downwardly, a pair of toggle members diagonally connecting the underside of said grate with a fixed support, means whereby said toggle may be prevented from breaking downwardly substantially beyond dead-center, means for breaking said toggle upwardly, and a weight tending to resist such upward breaking and thereby tending to counterbalance the weight of the grate.

3. A structure as specified in claim 2 which includes adjustable means for limiting the downward break of the toggle.

4. A structure as specified in claim 2 in which the weight specified is adjustable.

5. In combination, a movable grate portion pivoted near one side, a pair of toggle arms connecting such grate portion with a rock-shaft in such a way as to form a diagonal support for the free edge of said grate portion when said toggle members are aligned, means whereby said toggles may be prevented from breaking downwardly, a weight adapted to resist upward breaking of the toggles and to urge the toggle members towards a line position when said toggles are broken, and a lever connected with said rock-shaft whereby said toggles may be broken upwardly or returned to the aligned position.

HENRY GENNEL.
